UNITED STATES PATENT OFFICE.

ANDREW DRESHER, OF WAPAKONETA, OHIO.

FUNNEL.

1,303,270.

Specification of Letters Patent. Patented May 13, 1919.

Application filed February 27, 1918. Serial No. 219,463.

To all whom it may concern:

Be it known that I, ANDREW DRESHER, a citizen of the United States, residing at Wapakoneta, in the county of Auglaize and 5 State of Ohio, have invented certain new and useful Improvements in Funnels, of which the following is a specification.

This invention relates to funnels, and more particularly to a funnel of the automatic type.

One of the main objects of the invention is to provide a funnel of simple construction and operation in which the funnel neck is automatically closed when the liquid 10 is being poured through the funnel into a container reaches a predetermined level in the container. A further object is to provide simple and efficient control means in conjunction with a control valve whereby the 15 valve is automatically closed when the liquid has reached the predetermined level. Another object is to provide a funnel having a closure valve adapted to fit snugly in the lower end of the body thereof so as to prevent passage of liquid through the neck, means being provided for forcing this valve 20 into closed or seated position, the valve operating means and the float control means being so related as to permit the valve to 25 be raised into inoperative or opened position, the valve being retained in this position by the float control means. Further objects will appear from the detailed description.

35 In the drawings:

Figure 1 is a central vertical section through a funnel constructed in accordance with my invention showing the valve in raised position,

40 Fig. 2 is a section taken substantially on line 2—2 of Fig. 1,

Fig. 3 is a section taken on line 3—3 of Fig. 1.

The funnel body 1 which is of inverted 45 frusto-conical shape is provided at its lower end, with the cylindrical pouring neck 2. Spaced guide bars 3 are secured in the neck 2 and extend diametrically thereof. These bars are provided with alined apertures at 50 their centers which slidably receive a valve rod 4 upon which is secured a frusto-conical valve 5 of such size as to fit snugly within the body 1 adjacent the upper end of neck 2, when in lowered position, thus effectually

55 preventing flow of liquid into and through the neck. A disk 6 is mounted on rod 4 and is secured against downward movement thereof by a pin 7 inserted through the rod. An expansion coil spring 8 is confined between the lower cross bar 3 and this disk 60 and acts to normally force rod 4 downwardly so as to hold valve 5 in seated position. A ring 9 is loosely secured to the upper end of rod 4 so as to permit the valve 5 to be raised into opened or inoperative 65 position permitting the liquid which is poured into the body of the funnel to flow about the valve into neck 2.

The lower end portion of rod 4 is cut away for one-half of its thickness to provide 70 a depending finger 10 and a contiguous cut-out or recess. A float rod 11 is rockably mounted on a supporting rod 12 which extends diametrically of neck 2 adjacent the lower end thereof, suitable collars 13 being 75 positioned adjacent each side of float rod 11 so as to prevent movement thereof longitudinally of rod 12. The upper end portion of rod 11 is cut out to provide a finger 14 and a contiguous recess, this finger and 80 recess of rod 11 coöperating with the finger 10 and recess of rod 4 so that, when the rod 4 is in raised position it will be secured against downward movement by rod 11, the two rods thus forming, in effect, a continuous member. Rod 11 is provided at its lower end, with a right angularly disposed arm 15 to the outer end of which is secured 85 a hollow metal float 16. By this means, when rod 4 is raised so as to lift the valve 5, the upper end of rod 11 engages with the lower end of rod 4, the float 16 serving to rock rod 11 about its axis for this purpose, thus setting the funnel or securing valve 5 in raised position. After the funnel has 90 thus been set the liquid may be poured therethrough into the container in the usual manner. When this liquid engages float 16, the float is raised so as to raise the outer end of arm 15 of rod 11 thus rocking rod 11 in such a manner as to disengage the upper end thereof, from the lower end of rod 4. This serves to relieve rod 4 which is forced downwardly by expansion spring 8, thus closing the valve 5 and cutting off the 100 flow of liquid from the funnel into the container automatically. In this manner, the float control means serves to secure the valve 105

in raised or inoperative position, while also serving to trip the valve and cause it to be moved into closed position.

What I claim is:

- 5 In a funnel, an inverted frusto-conical body provided with a depending pouring neck, a valve rod passing therethrough, guide bars in said neck for guiding the vertical movement of the valve rod, a valve carried by said rod and adapted to close the lower end of the funnel body when the rod is in a lowered position, a collar mounted on said valve rod adjacent the end thereof, an expansion spring positioned 10 between the lower guide bar and the said collar for normally forcing the valve into operation, a float rod fulcrumed in the lower end of the neck beneath the valve rod, said float and valve rods having their upper 15

and lower ends respectively, adapted to co- 20 operate with each other forming a continuous member, and a float secured to the lower end of the float rod for rocking the upper end thereof out of engagement with the lower end of the valve rod when raised upwardly thereby releasing the valve so that it may move downwardly to a closed position, said float also serving to move the upper end of the float rod into engagement with the lower end of the valve when the 25 valve is drawn upwardly.

In testimony whereof I affix my signature in presence of two witnesses.

ANDREW DRESHER.
